UNITED STATES PATENT OFFICE.

GEORGE J. SCHNEIDER, OF DETROIT, MICHIGAN.

ELECTRICAL WATER-PURIFYING APPARATUS.

1,217,643.

Specification of Letters Patent. Patented Feb. 27, 1917.

Application filed August 23, 1915. Serial No. 46,978.

To all whom it may concern:

Be it known that I, GEORGE J. SCHNEIDER, a citizen of the United States of America, residing at Detroit, in the county of Wayne 5 and State of Michigan, have invented certain new and useful Improvements in Electrical Water-Purifying Apparatus, of which the following is a specification, reference being had therein to the accompanying drawings.

The invention relates to apparatus for electrically purifying water, and it is the object of the invention to obtain a portable instrument, simple in construction and thoroughly protected, so that it may be safely used by an inexperienced operator. It is a further object to prevent danger of short circuiting or the contamination of the water by poisonous electrolytic products.

In the drawing:

Figure 1 is a perspective view of the apparatus with the cap and outer casing removed;

Fig. 2 is a perspective view of the outer casing; and

Fig. 3 is a longitudinal section.

A and B are the electrodes which are preferably formed of bars of aluminum. These electrodes are secured to an insulator head 30 C on which the electrical terminal connections are mounted, and the opposite ends of the electrodes are also preferably attached to an insulator head D. E is an outer casing or guard for protecting the electrodes, and 35 which may be also formed of aluminum, and is provided with perforations F for the circulation of the water.

The electrical conductors used for conveying the current are usually formed of copper 40 wire, which under electrolytic action will form a poisonous salt. To avoid any possibility of electrolysis of the copper I have provided a construction of terminal head which is water proof and in which the connections are sealed. This is preferably 45 formed by a cap member G of insulating material, which engages a shouldered bearing H on the head C and is secured by suitable means such as the screws I. Within 50 the recess of the cap the terminals of the copper wire J are secured to binding screws K, which latter pass through the insulator head and engage the electrodes A and B. Between the binding screws K is a fin L of 55 insulating material, preferably formed integral with the head C. M is a flexible water-

proof tube, preferably formed of rubber tubing, which covers the conductors and extends into the cap G. The inner end of this tube is provided with an enlarged head N, 60 which is pressed by the fin L into contact with the inner face of the cap so as to form a water tight seal. Thus, where the entire instrument is immersed in water, there will be no possibility of penetration of the water 65 into the recess within the cap, and consequently the copper terminals are protected.

With an instrument constructed as described in use, the operator merely attaches the conductors to a source of current and then immerses the instrument in a vessel containing the water to be purified. The perforations F permit circulation of the water into and out from the casing E, and the latter shields the electrodes so as to avoid danger of short circuiting. The copper terminals, being protected by the cap G, are not subjected to electrolytic action, thereby avoiding, first, the contamination of the water, and second, destruction of the electrical contact.

What I claim as my invention is:—

1. An apparatus for purifying water, comprising spaced electrodes, a head associated with said electrodes at one end of the same, 85 binding screws passing through the terminal head and engaging the respective electrodes securing the latter to the head, conductors engaging said binding screws, and a cap detachably engaging the head and inclosing 90 said binding screws, said cap being apertured to give passage to said conductors.

2. An apparatus for purifying water, comprising a pair of spaced electrodes, an insulator head secured to said electrodes at one 95 end of the same, conductors attached to said electrodes upon said head, a perforated metallic casing inclosing said electrodes, having screw-threaded engagement with said insulator head, and a cap secured to said insulator head sealing the connection between said electrodes and conductors.

3. An apparatus for purifying water, comprising spaced non-corrodible electrodes, a head to which said electrodes are attached, conductors connected with said electrodes upon said head, a flexible waterproof tubing surrounding said conductors, and a cap surrounding the connections between said conductors and electrodes and forming a sealing joint with said tube.

4. An apparatus for purifying water, com-

prising spaced non-corrodible electrodes, a head to which said electrodes are attached, terminals carried by the head respectively connected with said electrodes, a fin upon 5 the head between the terminals, a cap inclosing said terminals having a sealing engagement with the head, and tube passing through the cap having an annular collar within the head, clamped between the cap and head by the engagement of the cap with the head.

5. An apparatus for purifying water, comprising spaced electrodes, a head to which said electrodes are attached, terminals car-

ried by the head respectively connected with 15 said electrodes, a cap inclosing said terminals having a sealing engagement with the head, and a tube passing through said cap having an annular collar within the cap, said collar being clamped between the cap 20 and head to seal the passage of said tube through the cap.

In testimony whereof I affix my signature in presence of two witnesses.

GEORGE J. SCHNEIDER.
